UNITED STATES PATENT OFFICE.

FRANK E. FARNHAM, OF PROVIDENCE, RHODE ISLAND, ASSIGNOR TO THE JEWELERS SUPPLY COMPANY, OF BIDDEFORD, MAINE, A CORPORATION OF MAINE.

SAFETY PIN CATCH.

Application filed August 10, 1921. Serial No. 491,207.

To all whom it may concern:

Be it known that I, FRANK E. FARNHAM, of Providence, in the county of Providence, State of Rhode Island, a citizen of the 5 United States, have invented certain new and useful Improvements in Safety Pin Catches, of which the following is a specification.

My invention relates to pin-catches for use 10 on brooches, bar-pins and other articles of jewelry, and consists of improvements in the structure and method of manufacture of the same.

The main object of the invention is to 15 provide a pin-catch having a rotatable keeper for holding the pin-stem in place in the catch to prevent accidental unfastening of the pin.

A particular object of the improvement is 20 to provide a more efficient pin-catch which may be economically manufactured from relatively light stock, but which at the same time will have greater strength and rigidity than the usual article of this type.

25 Another object of the improvement is to provide a device of the type specified in which the parts may be more easily constructed and assembled in the manufacturing process, and which may also be more easily and conveniently attached to the brooch or pin body in applying it to the article of jewelry.

A further object of the improvement is to 30 provide a device which will rest more firmly on the piece to which it is to be attached during the operation of soldering it thereto, and which will be securely held in place by the solder without danger of its parts spreading or opening.

40 Another object of the improvement is to provide a device in which the solder will not run away from the joint and tend to clog the operation of the rotatable keeper which locks the pin in the catch.

45 Another object of the improvement is to provide a catch in which the rotatable keeper has a more extended bearing contact whereby it is held against side-play or cramping and thus prevented from working loose.

50 Another object of the improvement is to provide a catch in which the keeper may be

more conveniently operated to shift it from open to closed position, or vice versa.

Another object of the improvement is to provide resiliently-operated detent-means 55 for holding the keeper normally in either open or closed position.

Still further objects of the improvement are set forth in the following specification which describes a preferred embodiment of 60 the invention as illustrated by the accompanying drawings. In the drawings:

Fig. 1 is an enlarged view of my improved pin-catch in side elevation, showing a portion of the body of the brooch to which it is 65 attached and illustrating the end of the pin-stem as locked in place in the catch;

Fig. 2, a part sectional end elevation of 70 the same, showing the keeper in open position;

Fig. 3, a similar view showing the keeper closed;

Fig. 4, a sectional view of the catch and keeper taken on the line 4—4 of Fig. 2, looking in the direction indicated by the arrow; 75

Fig. 5, a plan view of the finished blank from which the catch is formed;

Fig. 6, a perspective view of the keeper in one of its forms;

Fig. 7, a part sectional view, similar to 80 Fig. 2, illustrating a modified form of the catch with the keeper shown in open position;

Fig. 8, a similar view of this form of the device showing the keeper closed; 85

Fig. 9, a vertical sectional view of this form of device taken on the line 9—9 of Fig. 7;

Fig. 10, a plan view of the blank from which this form of catch is constructed; 90

Fig. 11, a bottom view of the base of this form of catch;

Fig. 12, a similar view of the base of the catch illustrating a modified form of construction; 95

Fig. 13, a side view of the catch showing a still further modification in the form of its base; and

Fig. 14, a bottom view of the base of the catch shown in Fig. 13. 100

Referring to the drawings, my improved catch comprises essentially a bifurcated

catch-member 2 constructed from sheet-metal and bent or folded at the top to provide two opposite legs 3 which are formed with circular depressions or sockets 4 adapted to receive the bearing-trunnions 5 of the rotatable keeper 6. In the embodiment of the invention illustrated in Figs. 1 to 6 the main catch-member 2 is constructed from a blank B, see Fig. 5, having an outline which 10 provides two circular disk-like portions 7 with a longitudinal pin-slot 8 extending from center to center thereof. The slot 8 is formed with circular ends 9 arranged concentrically of the disk-portions 7 which are 15 connected at the center of the blank by two opposite strips or tabs 10. Projecting from the outer ends of the disk-portions 7 of the blank are extensions 11 which are hollowed out to form substantially bell-shaped base- 20 portions 12 terminating in flat edges 14 adapted to be secured to the back of the pin body or brooch C represented in Fig. 1. The two disk-portions 7 of the blank B are cupped out to form the circular recesses 25 which provide the bearing-seats or sockets 4 for the trunnions 5 of the keeper 6, as later explained. Arranged in opposite relation on the rims of the sockets 4 are rounded teats 17 and 18 projecting outwardly there- 30 from to provide detent-stops which cooperate with suitable depressions on the side of the keeper 6 to lock the latter in its open and closed position in the manner and for the purpose as later more fully explained.

35 It will be understood that the above described construction of the catch-member 2 is accomplished by cutting the blank B from sheet-metal and forming it in suitable dies operated in a drop or press. The keeper 6, 40 see Fig. 6, is likewise blanked out from sheet-metal and struck up in dies. In general it consists of a main hook-like portion provided with a radial slot 20 corresponding to the pin-slot 8 in the catch-member 2. 45 Struck up from the sides of the keeper 6 are the circular trunnions 5 for engaging the sockets 4 of the catch-member 2 to adapt the keeper to rotate on the catch. Projecting diametrically from the opposite sides of the 50 rim of the keeper 6 are two lugs or finger-pieces 21, 22 which serve as the means for manually rotating the keeper on the catch. The finger-pieces 21 and 22 are bent at right-angles or offset at 23 to form shoulders 55 24 adapted to bear against the rim of the circular portions 7 of the catch-member 2, whereby to serve as an auxiliary bearing for the trunnions of the keeper 6 to prevent the latter from rocking or cramping laterally of its bearings on the catch. On each 60 side of the keeper 6 is an arcuate groove 25 arranged concentrically of the trunnions 5, and at the ends of the grooves are circular depressions 26 and 27 which cooperate with the teats or projections 17 and 18 on the

sides of the catch 2 in the manner as later explained.

In assembling the improved form of catch above described the blank B is bent at two points laterally of the connecting-strips or tabs 10, as represented by the dash-lines *a—a* and *b—b* in Fig. 5. In this manner the two disk-portions 7 of the blank are folded into opposite relation, as illustrated in Fig. 1, and the keeper 6 is inserted between 70 the sides 3 of the catch-member 2 with its trunnions 5 seated in the bearing-sockets 4, see Fig. 4. With the parts in this relation the finger-pieces 21 and 22 will project beyond the marginal edges of the circular 80 portions 7 of the catch-member 2 with their offset, shouldered portions 24 bearing on the rim of the catch. The assembled catch in this form provides a complete article of commerce known as a jewelry finding, and such articles are sold in large numbers to the trade. In applying the device to use the catch is generally mounted on the pin body or on the back of the brooch by soldering it thereto. To attach it to the article of 85 jewelry the catch is grasped in a pair of pliers and set in place by resting its base 12 on the body of the brooch C, as shown in Fig. 1. The enlarged base of the catch, 90 see Figs. 2 and 3, provides a firm support 95 so that the catch is not liable to be tipped over or upset and the extended bearing of the base on the body C allows for a secure fastening of the catch in place when the solder is flowed to its joint. When attached 100 to the pin or brooch body in this manner the two sides 3 of the catch-member 2 are held rigidly in spaced relation at the top by the bent or folded strips 10 which serve 105 as braces or cross-struts therefor; while the opposite base-portions 12 of the member being both united to the body C hold the sides rigidly at the bottom. In this way 110 a much stiffer and stancher structure is provided so that the stock from which the catch is constructed may be much thinner and lighter than that usually employed without sacrificing strength.

When applied to use the improved catch operates in the manner as next explained: 115 Referring to Fig. 2, the catch is here shown with the keeper 6 turned to open position with its radial slot 20 registering with the pin-slot 8 in the sides of the member 2. It will be noted that the pin-slot 8 in the 120 sides of the catch is arranged vertically so that it is open at the top, which is the preferred arrangement as providing for greater convenience in seating the pin therein. To lock the pin-stem P in the catch it is only 125 necessary to press its point-end down into the slot 8 and to then turn the keeper 6 to the position shown in Fig. 3. The keeper 6 is turned on the catch by simply pressing down on the finger-piece 21. When the 130

keeper 6 is turned to open position the finger-piece 21 strikes against one of the cross-strips or tabs 10 which serves as a stop to prevent it from being turned too far, see

5 Fig. 2; and when it is rotated to closed position, see Fig. 3, the other finger-piece 22 strikes against the opposite strip 10 to restrain its movement. Referring again to Fig. 2, when the keeper 6 is in open position 10 the detent-projection 17 is seated in the depression 26 on one side of the keeper 6, while the projection 18 on its other leg is engaged with the depression 27 on the opposite side of the keeper. Now, when the keeper 6 is rotated to its opposite position, 15 shown in Fig. 3, the projections 17 and 18 will ride up out of the depressions 26 and 27 and slide in the grooves 25 to allow a free turning movement of the keeper. As the keeper reaches its closed position the 20 projections 17 and 18 snap into the depressions 28 and 29 and in this manner a spring detent-action is effected which tends to prevent accidental movement of the keeper. 25 from either open or closed position. It is also to be observed that the provision of the grooves 25 allows the keeper to be turned without undue resistance after its detents have once been released from the end 30 depressions. In this way all undue friction and wear on the parts is eliminated so that this feature of construction provides a novel and improved advance in the art.

In Figs. 7 to 10 I have illustrated another embodiment of the invention in which the catch is constructed in the form of a hook having an undercut side opening 30. The blank B' for this type of catch, shown in Fig. 10, is shaped to provide two opposite circular hook-portions 31 joined together at the center by a single narrow strip or tab 32 or, if desired, a double cross-strip may be employed as in the first described construction. As with the previously described type of catch, the blank B' is folded across the connecting strip 32 at points indicated by the dash-lines a—a and b—b, and in this manner a bifurcated structure is formed, as shown in Fig. 9. The strip or tab 32 ties together the two sides 3 of the catch at the top, while also bracing them apart; and the two opposite base-portions 33 may be soldered or otherwise firmly united to the body of the brooch. Referring to Figs. 10 and 11, I have here illustrated a modification in the form of the base of the catch which provides an integral tie or lock for the two sides of the catch at its base. The base of one leg of the catch is here shown as extended at either side to form hook-portions 34. As shown more particularly in Fig. 11, when the sides of the catch have been folded into opposite relation the hook-portions 34 on the leg 33 are bent at right-angles and

hooked over the edges of the opposite leg 33 to form a box-like structure which provides a firmer support when the catch is mounted in place on the brooch.

Fig. 12 illustrates a still further modification in the form of the base of the catch in which its sides or legs 35 are provided with downwardly projecting lugs 36 bent into angular shape with their edges abutting to form a hollow square stud. The purpose of this construction is to provide for fastening the catch in an opening or perforation in the pin or brooch body by inserting the stud therethrough and swaging or rivetting over the ends of the lugs 36. 70 75 80

Figs. 13 and 14 show the catch constructed with a still different form of base, its sides 3 being flanged outwardly at 38 to form an enlarged bottom which will give a more extended bearing surface for its support while also tending to prevent the solder from flowing upwardly away from the joint and reaching the bearing for the keeper. 85

With the form of catch illustrated in Figs. 7 to 9 and 13 the keeper 40 is constructed with a single finger-piece 41 which is pushed upwardly to open the catch, as shown in Fig. 7, and pressed downwardly to close it, see Fig. 8. As herein shown the finger-piece 41 is formed as a straight projection on the side of the keeper 40 and is adapted to strike against the upper cross-strip 32 to limit the movement of the keeper in one direction and to engage the base of the catch to arrest its movement in the opposite direction. In some cases I may form the finger-piece with a bent or offset portion, as shown in Fig. 6, and when so constructed its shoulder will ride on the rim of the catch to steady its bearing in the sockets 4, while also acting as a stop when it strikes against the edge of the base-portion of the leg of the catch.

It will be observed from the foregoing description that my invention provides an extremely simple yet strong and rigid pin-catch which may be more securely fastened to the brooch or other article of jewelry, and which is more convenient to operate and more durable in use. The main catch-member has its opposite sides tied together and braced at the top by one or more cross-strips or struts so that when it is temporarily held together at the bottom by a suitable tool it may be more easily soldered in place while insuring that its parts will bear the proper operative relation. That is to say, the strut or cross-tie at the top of the catch-member serves to hold the two sides or legs of the catch from spreading or being bent out of alinement and hence the keeper which is seated in the socket-bearings on the sides of the catch is prevented from binding thereagainst and from cramping or working loose therein. The addi- 130

tional means for tying the legs of the catch together at the bottom provides for strengthening and stiffening the whole structure of the catch while also rendering it easier to assemble and apply to the piece on which it is used. My improved catch rests firmer on the piece while being soldered, the solder will not run up too far from the base, and when finished its sides 10 cannot open up or spread. On account of the inherent strength and stiffness of the catch, due to its improved structure, it may be made of much lighter stock, thus materially cheapening the cost of manufacture 15 when it is constructed from precious metal. Though much lighter in weight and more compact in size than the usual device of this type of article it will take a larger pin-stem and is therefore adapted for a wider 20 range of use.

In operation my improved catch is more conveniently opened and closed by a slight pressure of the fingers, yet nevertheless it locks the pin securely in place through the 25 automatic operation of the improved detent-means which controls the action of the keeper.

While I have herein shown and described my improved catch in a preferred embodiment it is to be understood that further modifications may be made in the form and structure of its parts without departing from the spirit or scope of the invention; therefore, without limiting myself as to the 35 exact construction as herein disclosed, I claim:

1. A safety-catch for pins, brooches or the like comprising a bifurcated catch-member having opposite parallel legs adapted to be 40 attached at the base to the body of the brooch and provided with a slot for receiving the pin-stem, a cross-strut integral with both legs of the catch-member and connecting its sides at a point relatively distant 45 from its base, and a keeper rotatable between the sides of the catch-member and adapted to close the opening of the pin-slot to lock the pin therein.

2. A safety-catch for pins, brooches or the like comprising a bifurcated catch-member having opposite sides adapted to be attached 50 at the base to the body of the brooch and formed with a radial pin-slot and circular bearings, a cross-strut integral with both 55 legs of the catch-member and connecting the sides of the member adjacent its top, and a slotted keeper seated in the bearings on the sides of the catch-member to adapt it to be rotated to close the opening of the pin-slot.

3. As a new article of manufacture, a safety pin-catch comprising a bifurcated sheet-metal catch-member having opposite parallel sides adapted to be attached at the base to the body of a brooch or the like, said 60 sides connected at the top by a folded strip

made integral with both legs of the catch-member, said member provided with a slot for receiving the pin-stem, and a keeper rotatably supported between the sides of the catch-member and having a slot adapted to 70 register with the pin-slot therein.

4. In a device of the type specified, the combination of a bifurcated catch-member having opposite parallel sides adapted to be attached at the base to the body of a brooch 75 or the like, said sides connected at the top by a cross-strut constructed integral with both legs of the catch-member, said member having means adapted to be locked in engagement to secure its sides together at the base, 80 said catch-member formed with a pin-slot for receiving the pin-stem, and a keeper rotatably mounted between the sides of the catch-member and having an opening registering with the pin-slot therein. 85

5. In a device of the type specified, the combination of a bifurcated catch-member having opposite circular side-portions which are slotted to provide a seat for the pin-stem, a keeper rotatably mounted between 90 the sides of said member and formed with an opening registering with the slots therein, said keeper provided with a finger-piece projecting outwardly beyond the rim of the catch-member and formed with a shoulder 95 adapted to bear on the circular edge thereof to steady the movement of the keeper in its bearings.

6. In a device of the type specified, the combination of a bifurcated catch-member having opposite parallel sides adapted to be attached at the base to the body of a brooch or the like and provided with a slot for the pin-stem, a keeper rotatable between the sides of said member and provided with 100 an opening adapted to register with the pin-slot, a detent-projection on one of said members adapted to slide in an arcuate groove 105 on the other member, and depressions at the ends of said groove into which the projection 110 snaps to hold the keeper in open or closed position.

7. In a device of the type specified, the combination of a bifurcated catch-member having opposite parallel sides adapted to be attached at the base to the body of a brooch or the like, said sides connected by an integral cross-strut at the top and provided with a slot for receiving the pin-stem, the base of said catch-member being adapted to 115 seat against the back of the piece to which it is attached and provided with lugs for insertion through an opening therein, and a keeper rotatably mounted between the sides 120 of the catch-member and provided with an opening adapted to register with the pin-slot 125 therein.

8. In a device of the type specified, the combination of a bifurcated catch-member having opposite parallel sides adapted to be 130

attached at the base to the body of a brooch or the like, said sides connected at the top by a cross-strut made integral with both legs of the catch-member and provided with a slot for receiving the pin-stem, the base of said catch-member being flanged outwardly to provide an enlarged flat seat adapted to

seat against the piece to which it is attached, and a keeper rotatably mounted between the sides of the catch-member and provided with an opening adapted to register with the pin-slot therein.

In testimony whereof I affix my signature.

FRANK E. FARNHAM.
